UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,288,914.

Specification of Letters Patent. Patented Dec. 24, 1918.

Application filed August 3, 1916. Serial No. 112,894.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawings.

10 My invention relates to typographical machines, such as linotype machines of the general organization represented in U. S. Letters Patent to O. Mergenthaler, No. 436,532, wherein circulating matrices are released 15 from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine from which they started.

20 More particularly, it relates to a machine 25 of the kind disclosed in my pending application for Letters Patent, Serial No. 52,999, filed September 28, 1915. In that machine, the matrices are stored according to font in 30 two magazines, each provided with its own series of escapements which effect the discharge of the contained matrices in the required order, and the two series of escapements are controlled by a common set of 35 actuating reeds which tend to actuate the corresponding escapements of both series at each operation; but this simultaneous actuation is prevented by locking devices, one for each series, which are operated in such manner 40 that when one is moved to inactive position, the other is simultaneously restored to active position, thus permitting the delivery of matrices from one magazine only at a time. Such operation of the escapement locking devices is effected by power 45 driven means under the control of two finger keys, one for each of the magazines, and which are actuated independently to cause the unlocking of the escapements of the corresponding magazine.

My present invention contemplates the use of a single finger key for changing back and forth between the two magazines, as above.

This will also avoid any possibility of mistake on the part of a careless or inexperienced operator who in the use of two finger keys might strike the wrong one.

In the accompanying drawings, I have illustrated my improvements merely in preferred form and by way of example and as applied to the particular style of machine mentioned, but obviously many changes and variations may be made therein, and in its mode of application, which will still be comprised within the spirit of my invention. 65 Generally speaking, I desire it to be understood that I do not limit myself to any specific form of embodiment, except in so far as such limitations are specified in the claims.

Referring to the drawings:

Figure 1 is a vertical section through a portion of a linotype machine of the kind described above, having my invention applied thereto;

Fig. 1^a is a section on the line 1^a—1^a of Fig. 1;

Fig. 2 is a section on the line 2—2 of Fig. 1;

Fig. 3 is a similar view showing the parts in different relative positions; and

Fig. 4 is a detached perspective of my improved devices.

As my improvements have been embodied in the kind of machine disclosed in my prior application, Serial No. 52,999, before referred to, I have confined the drawings to such parts thereof as are immediately concerned. If desired, reference may be had to such application for further and complete illustration and description of the remainder of the machine.

Referring to Fig. 1, the matrices X are stored according to font in one or the other of the magazines B, only two of which are shown but of which a greater number might be employed if desired. The matrices are released from their corresponding magazine by the escapements C and pass through one or the other of the throats D¹ into the vertical channeled raceway D, whence they are carried to the assembler and composed in line in the customary way.

The escapements C are of the usual construction, each comprising a rocking lever and a pair of pawls, which latter are projected alternately into the corresponding

magazine channel to control the release of the contained matrices. The escapements for each magazine are supported in series in the bar or frame C^8 , which may be connected directly to the magazine or pivotally secured to the magazine base frame. The escapements of both magazines are controlled by a single series of actuating members or reeds C^2 formed with the rearward projections C^{11} overlying the forward arms of the small levers C^1 pivoted to the escapement supporting frame C^8 , and which, under the influence of the members C^2 , act to rock the corresponding escapements of the two magazines simultaneously in one direction against the force of the springs C^4 tending to rock them in the opposite direction.

Attached to the lower ends of the actuating members C^2 are the springs C^3 pulling downwardly thereon from a relatively fixed part of the machine and of sufficient strength to overcome the action of the springs C^4 so as to hold the lowermost pawls of the escapements in engagement with the leading matrices in the magazines, which are thus prevented from escaping therefrom. To permit the release of said matrices, therefore, it is necessary to raise the actuating members C^2 against the force of their springs C^3 , when the lighter springs C^4 will be allowed to act; and this movement of the actuating members is effected by the pivoted levers C^5 engaging beneath the projections C^{12} thereon and arranged to be rocked upwardly by the vertically guided rods C^6 operated from the main keyboard mechanism in the usual way.

Since the actuating members C^2 control the escapements of both magazines, their operation would result in the release of matrices from both at the same time were other means not provided. Each series of escapements, therefore, is equipped with the well known transverse rock shaft H which is rotatably mounted in the supporting frame C^8 and arranged in proximity to the rear ends of the escapement levers, the shaft being cut away or recessed in the usual way so that in one position it will lock the escapements, while in another it will permit their operation. The shafts H are provided at one end with crank arms which are connected by the vertical rods H^4 to the pivoted levers H^6 operated through the medium of the shorter rods H^7 , $H^{7'}$, by the power driven cam yokes H^8 , $H^{8'}$. The rods H^4 are constantly urged upward to move their connected rock shafts to locking position by the springs H^5 which are connected to the pivoted levers H^6 and pull upwardly thereon from a fixed part of the machine. When the rods H^4 are depressed against the action of the springs H^5 by the cam yokes, they are held down by the spring-actuated locking plate H^{11} (Fig. 1^a) which is provided with

hooks H^{12} adapted to engage over the rear arms of the levers H^6 . The upper ends of the hooks H^{12} are beveled or inclined so that when a lever H^6 is rocked downward, the locking plate is displaced to allow the lever to pass and thereafter snaps back to locate the corresponding hook across the lever and hold it down with the connected escapement rock shaft in unlocking position. The displacement of the locking plate by either one of the levers H^6 releases the other if the latter had previously been locked down, and consequently permits the corresponding escapement rock shaft to be returned to its locking position by the spring H^5 . In other words, the arrangement is such that the movement of one of the rock shafts H to unlocking position restores the other to locking position, and vice versa, thus allowing the matrices to be released from only one magazine at a time.

As before stated, the power exerted in effecting the operation of the rock shafts is derived from the two cam yokes H^8 and $H^{8'}$. They are of the ordinary construction, being pivoted at one end and arranged with their opposite ends in position to engage and operate the overlying rods H^7 and $H^{7'}$, connected to the rock shafts. Between their ends, the yokes are provided with the rotary cams or eccentrics H^{20} and $H^{20'}$, adapted to be rotated by the underlying power driven roll H^{23} . Normally, however, the yokes are supported at their free ends upon the angular pivoted dogs H^{22} and $H^{22'}$, which hold them at such height as to maintain the cams out of engagement with the roll, the cams in this position of the parts being held against rotary movement by the fixed stops H^{21} and $H^{21'}$, on the framework. When the dogs are moved, the cam yokes are tripped and allowed to drop, with the result that the cams thereon are disengaged from the fixed stops and come into contact with the power driven roll, causing the yokes to be rocked upwardly to raise the actuating rods. The tripping movement of the dogs H^{22} is effected by means of the vertical slides H^{24} and $H^{24'}$, suitably supported in the framework.

The parts so far described and their manner of operation are fully set forth in my pending application above mentioned, and the corresponding parts are indicated by substantially the same letters of reference. However, in said application, the vertical slides H^{24} and $H^{24'}$ are connected to two distinct finger keys which are actuated independently to control the selection of one or the other of the magazines.

In carrying out my present invention, I make use of a single finger key H^{10} to control the operation of the two slides, means being provided for connecting the key to the slides alternately at its repeated actuations,

so that it may alone change back and forth between the two magazines in the required order. In the present instance, such means comprise a vertical rocking lever P centrally pivoted to the framework, as at P^1 , and provided at its lower end with a pivoted latch or pawl P^2 . This pawl rests at its free end upon the rear arm of the key lever H^{10} and is formed at its upper edge with a raised portion P^4 adapted to engage overlying bracket plates P^5 and $P^{5'}$ attached to and projecting inwardly from the cam tripping slides H^{24} and $H^{24'}$, respectively, the engagement of the latch with one or the other of the bracket plates being controlled by the position of the lever P which is arranged to be rocked to the right and left for that purpose. The latch P^2 is also formed at its free end with an enlarged or laterally extended bearing head P^8 to maintain its connection with the finger key H^{10} in either one of its two positions. As a result of the foregoing construction, when the key lever H^{10} is depressed, its motion is transmitted to the pivoted latch P^2 , which is rocked upwardly relatively to the lever P to raise one or the other of the slides H^{24} , $H^{24'}$, to trip the corresponding cam yoke, and consequently through the connections before described to move the associated escapement rock shaft H to unlocking position.

The rocking lever P is forked at its upper end, having two oppositely extending prongs P^6 , which latter are provided with forwardly projecting pins P^7 and $P^{7'}$, arranged to be engaged by inclined or cam-shaped pieces P^8 and $P^{8'}$, carried by the actuating rods H^7 and $H^{7'}$, respectively, the relation of the parts being such that the lever is rocked to the left and right by the actuating rods as they are alternately raised by the corresponding cam yokes.

The action of the parts will now be clear: When the lever P is shifted to the right, its pivoted latch P^2 is located beneath the bracket plate P^5 on the cam releasing slide H^{24} , thus connecting this slide with the finger key H^{10} , and the same movement of the lever brings its projecting pin P^7 in engaging relation to the cam piece P^8 on the actuating rod H^7 , see Fig. 2. In this position of the parts, when the key lever H^{10} is depressed, the yoke H^8 is tripped and allows its cam H^{20} to fall into engagement with the power driven roll H^{23} , thus causing the upward rocking of the yoke and the raising of the overlying actuating rod H^7 , whose movement is imparted to the corresponding pivoted lever H^6 , which, through its connections with the lower rock shaft H , rotates the latter to unlocking position, where it is held by the locking plate H^{11} . Also during this action, the actuating rod H^7 , due to the engagement of its cam piece

P^8 with the pin P^7 , rocks the lever P to the left to the position shown in Fig. 3, thus bringing the pivoted latch P^2 beneath the bracket plate $P^{5'}$ on the cam slide $H^{24'}$ to connect the latter with the finger key, 70 and at the same time locating the projecting pin $P^{7'}$ of the lever in engaging relation to the cam piece $P^{8'}$ on the actuating rod $H^{7'}$. With the parts in this position, the next operation of the finger key H^{10} 75 trips the cam yoke H^8 , which is thereupon rocked upwardly by the engagement of its cam $H^{20'}$ with the power driven roll H^{23} and operates the other pivoted lever H^6 to move the upper rock shaft H to unlocking 80 position. The slide $H^{7'}$ in this last action, and due to the engagement of its cam piece $P^{8'}$ with the pin $P^{7'}$, rocks the lever P again to the right and restores it to its original position, as shown in Fig. 2. In other 85 words, the construction is such that the finger key H^{10} is connected to the two cam yokes alternately by its repeated actuations, and thus operates the locking rock shafts of the two magazines alternately to select first 90 one and then the other, such change taking place each time the key is actuated. It has been before explained that when one of the escapement rock shafts is moved to inactive position, the other is restored to active position, this action being secured by the co-operation of the locking plate H^{11} with the pivoted lever H^6 .

In order to maintain the rocking lever P in its different positions, the actuating rods H^7 and $H^{7'}$ are provided with small hooks P^9 and $P^{9'}$, adapted to embrace the projecting pins P^7 and $P^{7'}$ thereon, the hooks on the two rods acting alternately as the lever P is shifted to the left and right in the manner before described. Thus, as shown in Fig. 2, when the lever occupies its position to the right, the hook P^9 on the rod H^7 engages behind the pin P^7 , and, as shown in Fig. 3, when the lever occupies its position to the left, the hook $P^{9'}$ on the rod $H^{7'}$ engages behind the pin $P^{7'}$. The relative arrangement of the hooks P^9 , $P^{9'}$, and cam pieces P^8 , $P^{8'}$, is such that the hooks are disengaged from the projecting pins P^7 , 115 $P^{7'}$ just prior to the engagement of the cam pieces therewith.

As previously stated, I have shown my improvements only in preferred form and by way of example and as applied to the 120 particular kind of machine specified, but obviously many modifications and alterations therein and in their mode of application will suggest themselves to those skilled in the art without departure from the scope 125 of the invention. Thus, the specific devices illustrated have been developed with particular reference to the structure disclosed in my previous application, one of my purposes being to adapt my invention thereto 130

with the minimum of alteration. But the broad principle involves the provision of any suitable mechanism whereby the escape-
ment locking devices may be operated by
power driven means under the control of a
single finger key in such manner that the
successive actuations of the key effect the
reverse operations of the locking devices to
change back and forth between the two
magazines. However, the particular devices
herein employed for this purpose are be-
lieved to be new in themselves, and are such
that they might be used to subserve a dif-
ferent function, as for instance in connec-
tion with the so-called double "e" arrange-
ment, wherein duplicate matrices are drawn
from alternate channels of a magazine.

Having thus described my invention, its
construction and mode of operation, what I
claim and desire to secure by Letters Patent
of the United States, is as follows:

1. In a typographical machine, the combi-
nation of two magazines each having a mov-
able matrix locking device, and mechanism
for moving one of said locking devices to
inactive position and the other to active po-
sition, and vice versa, the said mechanism in-
cluding power driven means operatively con-
nected to the locking devices, a single finger
key controlling the operation of said power
driven means, and means whereby the suc-
cessive actuations of the key effect the re-
verse movements of the locking devices.

2. In a typographical machine, the combi-
nation of two magazines each having a mov-
able matrix locking device, and mechanism
for moving one of said locking devices to
inactive position and the other to active po-
sition, and vice versa, the said mechanism in-
cluding two power-actuated devices connect-
ed to the respective locking devices, a single
finger key, and means controlled by the suc-
cessive actuations of said key for effecting
the independent operation of the power-
actuated devices alternately.

3. In a typographical machine, the combi-
nation of two magazines each having a mov-
able matrix locking device, and mechanism
for moving one of said locking de-
vices to inactive position and the other to ac-
tive position, and vice versa, the said mech-
anism including two independently operable
actuating devices connected to the locking
devices, a single operating element, auto-
matic means for connecting said element to
the two actuating devices alternately, and
locking means to hold either one of the ac-
tuating devices in its operated position but
adapted to be disengaged automatically by
the subsequent operation of the other.

4. In a typographical machine, the combi-
nation of two magazines each having a mov-
able matrix locking device, and mechanism
for moving one of said locking devices to
inactive position and the other to active

position, and vice versa, the said mechanism including two independently operable actuating devices connected to the locking devices, a single operating element, means controlled by the successive operations of said element for connecting it to the two actuating devices alternately, and locking means to hold either one of the actuating devices in its operated position but adapted to be disengaged automatically by the subsequent operation of the other.

5. In a typographical machine, the combi-
nation of two magazines each having a mov-
able matrix locking device, and mechanism
for moving one of said locking devices to
inactive position and the other to active po-
sition, and vice versa, the said mechanism in-
cluding two power operated actuating de-
vices connected to the locking devices, a
single finger key controlling the operation
of said actuating devices, means whereby the
successive actuations of said finger key ef-
fects the operation of the two actuating de-
vices alternately, and locking means to hold
either one of the actuating devices in its
operated position but adapted to be disen-
gaged automatically by the subsequent oper-
ation of the other.

6. In a typographical machine, the combi-
nation of two magazines each having a mov-
able matrix locking device, and mechanism
for moving one of said locking devices to
inactive position and the other to active po-
sition, and vice versa, the said mechanism in-
cluding two independently operable actuating
devices operatively connected to the locking
devices, a pair of cam yokes for oper-
ating the actuating devices, a single finger
key, means whereby the successive actu-
ations of the key throws the cam yokes into
action alternately, and locking means to hold
either one of the actuating devices in its op-
erated position but adapted to be disengaged
automatically by the subsequent operation
of the other.

7. In a typographical machine, the combi-
nation of two magazines each having a mov-
able matrix locking device, an independ-
ently operable actuating device connected
to each locking device for moving it to lock-
ing and unlocking position, means whereby
the unlocking movement of one of said actu-
ating devices effects the locking movement
of the other, a single operating element, and
means controlled by the successive operations
of said element for connecting it to the two
actuating devices alternately.

8. In a typographical machine, the combi-
nation of two magazines each having a mov-
able matrix locking device, an independ-
ently operable actuating device connected to each
locking device for moving it to locking and
unlocking position, means whereby the un-
locking movement of one of said actu-
ating devices effects the locking movement of

the other, power driven means for effecting the independent operation of said actuating devices alternately, and a single finger key controlling the operation of said power driven means.

9. In a typographical machine, the combination of two magazines each having a movable matrix locking device, an independently operable actuating device connected to each 10 locking device for moving it to locking and unlocking position, means whereby the unlocking movement of one of said actuating devices effects the locking movement of the other, a pair of cam yokes for effecting the 15 independent operation of said actuating devices, a single finger key, and means whereby the successive actuations of said key throws the two cam yokes into action alternately.

10. In a typographical machine, the combination of a plurality of magazines each 20 having a movable matrix locking device, and mechanism for moving one of said locking devices to inactive position and restoring another to active position, the said means including power driven means operatively connected to the respective matrix locking devices, a single finger key controlling the operation of said power driven means, and means whereby the successive actuations of 25 the finger key effects the movement of a different locking device to inactive position.

11. In a typographical machine, the combination of a plurality of magazines each 30 having a movable matrix locking device, an independently operable actuating device connected to each of the matrix locking devices for moving it to locking and unlocking position, means whereby the unlocking movement of one of said actuating devices effects 35 the locking movement of another, a single operating element, and means controlled by the successive operations of said element for connecting it to the actuating devices successively.

45 12. In a typographical machine, the combination of a plurality of magazines each having a movable matrix locking device, an independently operable actuating device connected to each of the matrix locking devices 50 for moving it to locking and unlocking position, means whereby the unlocking movement of one of said actuating devices effects the locking movement of another, power driven means for effecting the independent 55 operation of said actuating devices in a definite repeating order of succession, and a single finger key controlling the operation of said power driven means.

60 13. In a typographical machine, the combination of a plurality of actuating devices, a single operating element therefor, and means for connecting the operating element to the actuating devices successively, the said means including a shiftable part through 65 which the connection is made, and a control-

ling member arranged to be operated by the actuating devices.

14. In a typographical machine, the combination of a pair of actuating devices, a single operating element therefor, and means 70 for connecting the operating element to the actuating devices alternately, the said means including a shiftable part through which the connection is made and a rocking lever carrying said shiftable part and arranged to 75 be moved in opposite directions by the two actuating devices alternately.

15. In a typographical machine the combination of a pair of actuating devices, a single operating element therefor, and means 80 for connecting the operating element to the actuating devices alternately, the said means including a shiftable part through which the connection is made, and a rocking lever carrying said shiftable part and arranged to 85 be moved in opposite directions by the two actuating devices alternately, together with means carried by the actuating devices for holding the lever temporarily in its different 90 positions.

16. In a typographical machine the combination of a plurality of actuating devices, a corresponding plurality of power actuated instrumentalities for operating them, a single controlling finger key therefor, and 95 means operated by the actuating devices for connecting the finger key to the several power operated instrumentalities in succession.

17. In a typographical machine, the combination of a plurality of actuating devices, a corresponding plurality of power actuated instrumentalities for operating them, a single controlling finger key therefor, and means for connecting the finger key to the power actuated instrumentalities in succession, the said means including a shiftable part through which the connection is made, and a controlling member therefor arranged 100 to be operated by the actuating devices. 110

18. In a typographical machine, the combination of a pair of actuating devices, a pair of cam yokes for operating them, tripping slides for the cam yokes, a single finger key, and means for connecting the finger key 115 to the cam tripping slides alternately, the said means being controlled by the actuating devices.

19. In a typographical machine, the combination of a pair of actuating devices, a pair 120 of cam yokes for operating them, tripping slides for the cam yokes, a single finger key, and means for connecting the finger key to the cam tripping slides alternately, the said means including a shiftable part through 125 which the connection is made, and a controlling member therefor arranged to be operated by the actuating devices.

20. In a typographical machine, the combination of a pair of actuating devices, a pair 130

of cam yokes for operating them, tripping slides for the cam yokes, a single finger key, and means for connecting the finger key to the cam tripping slides alternately, the said 5 means including a pivoted lever arranged to be rocked in opposite directions by the actuating devices, and a part carried by said lever and through which the connection between the finger key and the cam slides is 10 made.

21. In a typographical machine, the combination of a pair of actuating devices provided with inclined or cam shaped pieces, a pair of cam yokes for operating the actuat-

ing devices, tripping slides for the cam 15 yokes provided with bracket plates, a single finger key, and a rocking lever formed at its upper end with projecting pins arranged to be engaged by the cam pieces on the actuating slides, and provided at its lower end with 20 a pivoted latch constantly engaged with the finger key and adapted to be shifted by the rocking lever into operative relation to the bracket plates on the two cam slides alternately. 25

In testimony whereof, I have affixed my signature.

DAVID S. KENNEDY.
